UNITED STATES PATENT OFFICE.

THEODORE BECKER, OF LANCASTER, OHIO, ASSIGNOR TO THE HOCKING VALLEY MANUFACTURING COMPANY, OF SAME PLACE.

GRAIN-DRILL.

SPECIFICATION forming part of Letters Patent No. 297,488, dated April 22, 1884.

Application filed January 7, 1884. (Model.)

To all whom it may concern:

Be it known that I, THEODORE BECKER, of Lancaster, Fairfield county, Ohio, have invented a new and useful Improvement in Grain-Drills, of which the following is a specification.

My invention comprises means for the more perfect regulation of the seed-delivery of those grain-drills in which a fluted feed-wheel is caused to revolve within the closely-inclosing passage-walls of a "cup" or funnel, and comprises a construction of such cup in which that part of the cup-wall which is on the receiving side of the feed-wheel is fitted for adjustment longitudinally of said wheel on the rear wall, the cup being divided on a vertical line following the rear curve of the feed-wheel. The stationary and the movable parts of the cup are each provided with a wing-extension that is flush with the feed-wheel's periphery, in order to permit such shift of the cup-wall without spillage of its contents.

It will be seen that the feed-wheel in my present improvement is capable of rotary motion only.

My invention further comprises a peculiarly constructed and attached shiftable delivery-spout.

In the accompanying drawings, Figure 1 is a perspective view of a grain-delivering mechanism embodying my improvements, the shiftable member of the cup being shown separate. Fig. 2 is a vertical section in the plane of delivery of my feed mechanism, including the upper portion of the delivery-spout. Figs. 3 and 4 are top views of my feed mechanism in the respective conditions of full-feed and of complete cut-off, a part of the shiftable cup-section being broken away in Fig. 3. Figs. 5 and 6 are sectional views on lines *x x* and *y y* of Fig. 4. Figs. 7 and 8 illustrate the mode of attaching and detaching the delivery-spout. Fig. 9 is a section on line *z z* of Fig. 2. Fig. 10 is a perspective view of a grain-drill of five places of delivery, applicable for use with my improvements.

A may represent a part of the grain-box floor of a grain-drill, *a* representing one of a number of outlets—one for each grain-deliv-

ery—and each conducting into its proper grain-cup.

The drawings show one of a series of grain-cups of identical form, and of which each consists of two sections or members—to wit, a stationary section, *B*, and a shiftable section, *E*, divided from the stationary section on a vertical line following the periphery of the feed-wheel and slideable on the former. The stationary section *B*, preferably in two parts, as represented, furnishes journal-bearing to the feed-wheel *C* and has the delivery-nozzle *D*. The section *B* is permanently fastened to the under side of the floor *A*, as shown, and has two cheeks, *b* *b'*, of which the cheek *b* has on the side next the shiftable section a semicircular contour flush with the periphery of the feed-wheel, as at *b''*, and the cheek *b'* has on the same side a semicircular contour flush with the bottoms of the flutings, as at *b'''*, whence it extends obliquely outward by a chamfer, *b'''*, to a wing, *F*, whose semi-cylindrical convexity is flush with the feed-wheel's periphery.

Ledges *b''* and *b'''* on the receiving side of the section *B* support and guide my shiftable section *E*.

The shiftable section *E*, which constitutes the supply-funnel, has a wing, *G*, and a cheek, *G'*, whose cylindrical concavities fit and slide upon the corresponding convexities of cheek *b* and wing *F* of the stationary cup-section *B*. A square (or other non-circular) eye in wheel *C* receives the correspondingly-shaped drive-shaft *H*, whose rotation is secured by any customary connection with a ground-wheel. The shiftable section *E* of each cup has a stud, *I*, which enters an orifice, *j*, in a bar, *J*, a handle, *j'*, on one or both extremities of which enables the said bar and its entire series of attached cup-sections to be shifted to the right or to the left, so as to expose more or less of the feed-wheel flutings, and to thus increase or diminish the feed action. In these adjustments the office of the wing *F* on the stationary cup-section will be seen to be to prevent the escape of grain from that portion of the shifting section which is for the time being thrown beyond the feed-wheel and its inclos-

ing-cheek; and the office of the wing G on the shiftable cup-section will be seen to be to "cut off" or render inoperative the whole or any portion of the feed-wheel flutings. For example, when shifted to the extreme left, section E is brought opposite the cylindrical surface of the stationary wing F, which then operates to completely close the delivery. (See Fig. 4.)

10 It will be seen that the entire section of cup which gives journal-bearing to the feed-wheel is stationary and has a stationary guard-wing, and that the shifting action is restricted to the funnel or supply-section having a movable 15 guard-wing; that said winged funnel is operated independently of both drive-shaft and feed-wheel, and that the capacity for delivery of the fluted wheel may be varied without affecting those of the supply and discharge passages with which said wheel co-operates.

The stationary member of the feed-cup has two projecting hooks, d d', which, being successively passed through notch or gate k' in flange k of delivery-spout K, as shown in Figs. 25 7 and 8, cause the suspension of said spout, either obliquely rearward for rear delivery, as shown in Fig. 1, and in the rear rank of delivery-spouts in Fig. 10, or obliquely forward for front delivery, as shown in the front rank. 30 of delivery-spouts in the same figure. This arrangement renders the device readily applicable to such two-rank drills, as illustrated in said figure.

It is obvious that any one or all the spouts 35 are of easy attachment, presentation, or removal at will.

I claim as new and of my invention—

1. In a grain-drill, the combination, with a fluted feed-wheel, of a cup having two winged 40 sections—to wit, one fixed section, B, in which said wheel is journaled, and having a delivery-spout, D, and one shiftable section, E, which constitutes the supply-funnel to said feed-wheel, and whose capacity and that of said delivery-nozzle remain unaffected by changes in 45 capacity of the feed-wheel—the whole being constructed and operated substantially as set forth.

2. In a grain-drill, the combination, with a fluted feed-wheel, of a cup divided longitudinally of the feed-wheel on a line following the periphery of the feed-wheel on the receiving side thereof, to provide one fixed and one shiftable section to slide on the rear wall of the fixed section, each section having a guard-wing, constructed and operating substantially as set forth.

3. In a grain-drill, the described combination, with a fluted feed-wheel, of a grain-cup having a fixed section in two parts, and a 60 shiftable section, a guard-wing on the fixed section, and a groove or recess in the rear of said section, and a guard-wing on the shiftable section, the latter being supported in the groove or recess, as set forth.

4. In a grain-drill, the described combination, with a fluted feed-wheel, C, of a grain-cup composed of two sections—to wit, a stationary section, B, which affords journal-bearing to said feed-wheel, and has a guard-wing, 70 F, whose cylindrically-convex surface is flush with the feed-wheel's periphery, and a shiftable section, E, which has a cylindrically-concave wing, G, adapted to fit and slide upon said wing F—in the manner set forth, and for 75 the purpose explained.

5. In a grain-drill, the described combination, with a fluted feed-wheel, of a cup composed of two sections—one fixed, the other 80 shiftable—a projection on the rear of the fixed section, and a projection or hook on the front thereof, for the purpose set forth.

6. The delivery-spout having exterior flange formed with a gate or recess, for the purpose 85 set forth.

7. In a grain-drill, the combination, with the delivery-nozzle D of the cup, of the hooks d d', and separable and reversible delivery-spout having exterior flange, k, formed with gate or recess k', substantially as set forth.

In testimony of which invention I hereunto set my hand.

THEODORE BECKER.
